(57) **CLAIM**

The ornamental design for container for liquid, as shown and described.

DESCRIPTION

1.1 is a perspective view of a design for a container for liquid, according to a first embodiment of the invention.

1.2 is a front view of the design of **1.1**.

1.3 is a back view of the design of **1.1**.

1.4 is a right side view of the design of **1.1**.

1.5 is a left side view of the design of **1.1**.

1.6 is a top view of the design of **1.1**.

1.7 is a bottom view of the design of **1.1**.

2.1 is a front view of a design for a container for liquid, according to a second embodiment of the invention.

2.2 is a back view of the design of **2.1**.

3.1 is a perspective view of a design for a container for liquid, according to a third embodiment of the invention.

3.2 is a front view of the design of **3.1**.

3.3 is a back view of the design of **3.1**.

3.4 is a left side view of the design of **3.1**.

3.5 is a right side view of the design of **3.1**.

3.6 is a bottom view of the design of **3.1**.

3.7 is a top view of the design of **3.1**.

4.1 is a perspective view of a design for a container for liquid, according to a fourth embodiment of the invention.

4.2 is a front view of the design of **4.1**.

4.3 is a back view of the design of **4.1**.

4.4 is a left side view of the design of **4.1**.

4.5 is a right side view of the design of **4.1**.

4.6 is a top view of the design of **4.1**.

4.7 is a bottom view of the design of **4.1**.

5.1 is a perspective view of a design for a container for liquid, according to a fifth embodiment of the invention.

5.2 is a front view of the design of **5.1**.

5.3 is a back view of the design of **5.1**.

5.4 is a left side view of the design of **5.1**.

5.5 is a right side view of the design of **5.1**.

5.6 is a top view of the design of **5.1**.

5.7 is a bottom view of the design of **5.1**.

(Continued)

- 6.1 is a front view of a design for a container for liquid, according to a sixth embodiment of the invention.
- 6.2 is a back view of the design of 6.1.
- 7.1 is a perspective view of a design for a container for liquid, according to a seventh embodiment of the invention.
- 7.2 is a front view of the design of 7.1.
- 7.3 is a back view of the design of 7.1.
- 7.4 is a left side view of the design of 7.1.
- 7.5 is a right side view of the design of 7.1.
- 7.6 is a top view of the design of 7.1.
- 7.7 is a bottom view of the design of 7.1.
- 8.1 is a perspective view of a design for a container for liquid, according to an eighth embodiment of the invention.
- 8.2 is a front view of the design of 8.1.
- 8.3 is a back view of the design of 8.1.
- 8.4 is a left side view of the design of 8.1.
- 8.5 is a right side view of the design of 8.1.
- 8.6 is a top view of the design of 8.1.
- 8.7 is a bottom view of the design of 8.1.
